UNITED STATES PATENT OFFICE.

JAMES H. GORDON, OF IRVINGTON, NEW JERSEY.

MACHINE FOR CRIMPING POLYGONAL CANS.

Application filed April 11, 1924. Serial No. 705,743.

To all whom it may concern:

Be it known that I, JAMES H. GORDON, a citizen of the United States, and a resident of Irvington, county of Essex, and State of New Jersey, have invented certain new and useful Improvements in Machines for Crimping Polygonal Cans, of which the following is a specification.

This invention relates to an improved machine for crimping, seaming or applying a tool for any other purpose at the edge of a polygonal can such as a square or oblong can.

The present specification, for the purpose of clearness of description, describes a crimping tool and it will be understood that this term includes seaming and other forms of tools such as rollers which may be employed in manipulating the sides or rims of polygonal cans.

The machine is designed to provide a head mounted in a support and which has a circular motion but which carries a tool or tools that are moved inwardly or outwardly on the rotating head so that the tool follows a polygonal path. The invention is compact and requires a relatively small space for its operative parts and is simple so that its continuous successful operation is assured.

The invention is illustrated in the accompanying drawings in which Figure 1 is a side view part of the machine being shown in section, this machine showing one type embodying the present invention. Figure 2 is an enlarged section of a part of the head of this machine and Figure 3 is a horizontal section broken away this sectionized portion being taken on a plane indicated by line 3-3 in Figure 2. Figure 4 is a section of the bottom of the head showing a modification for use with an oblong can this section being taken on line a-a in Figure 6. Figure 5 is a similar section taken on line b-b in Figure 6. Figure 6 is a horizontal section of the head shown in Figures 4 and 5.

The machine consists of any desired form of standard 10 and is usually provided with a holder 11 to support the can 12 and adapted to be elevated by means of the foot lever 13 connected by the system of levers 14 with the holder 11. The can is held in fixed position by any suitable means such as the rod 15 pressed down by the handle 16, the rod extending down through a sleeve 17 in the support having the bearing 18 at the top and the bearing 19 below it.

This holding means of the can, of course, can be changed to fit the circumstances and can be altered in its structure so long as it firmly holds the can 12 against turning while suitable tools traverse the outside of it for crimping, seaming and the like. The head 20 rotates on the support being fastened to the sleeve 21 and being rotated by the gear 22 in mesh with the gear 23 which is on the shaft 24 and is driven from the pulley 25 by the gear 26.

A crimping tool or tools, usually two or four in number, are secured to the head and project below it. In the drawing the tool is illustrated at 27 and is mounted on a shaft 28 which has the eccentric portion 29 the function of this eccentric arrangement being to provide a setting in of the roller or tool 27 when it is necessary to take up wear. An adjusting sleeve 30 with the pin 31 is utilized for holding the shaft in its adjusted position.

The tool itself is caused to revolve by reason of the sleeve 32 driven by a ring gear 33 which is in mesh with the teeth 34 of the gear 35 on the sleeve 36 which is provided with a gear 37 driven from a gear 38 on the shaft 24. The sleeve 32 is also eccentric because it must be slowly turned to bring the crimping tool 27 closer to the centre of the can at each revolution so that there is a gradual squeezing of the can until the required number of revolutions have been completed to finish the operation.

So far as described, the machine is of a type now in existence and will operate on round cans since the crimping tool will be carried around in a circular path slowly getting smaller to a limited extent. The improvement lies in causing this circular path of the head to be so modified so far as the tool is concerned, to cause the tool to follow a polygonal path.

The form I illustrate for doing this consists in mounting the previously described structure in an eccentric 39 which is rotated since it is provided with teeth 40 so that it forms a pinion in mesh with the teeth 41 of the gear 42 which is fastened by a suitable means around the fixed sleeve 17. The result of this arrangement is that the head rotates the pinion 40 in mesh with the gear 41, the parts of course, being properly proportioned, to be extended or carried usually from the centre of the head at certain points in its rotation the maximum of such out-

ward movement being opposite where the outer corners 43 of the square can 12 are located. By the same mechanism the eccentric 39 would be moved to swing the tool inward, its maximum inward movement being opposite the centre of each flat side 44 of the can 12. This forces the crimping tool to pursue or follow a polygonal path and in Figures 1, 2 and 3 the construction provides for the head with its circular motion having a crimping tool which carried it but that tool follows a polygonal path.

In Figures 4, 5 and 6 I show a modification as designed to cause the crimping tools to follow around the sides of an oblong can. In the form shown the crimping rollers are four in number and are mounted similarly to those described hereinabove. They are however, retarded in the movement of the eccentric 39 and speeded up in the movement of this eccentric according to whether the tool happens to be working on the short or the long side of the oblong can.

The form that I illustrate for carrying out this mechanical movement embraces one gear 45 which is in the shape of a ring and is in mesh with the gear 40 on the roller 27 on the eccentric 39 this ring being in engagement with the gear 40 on the two rollers illustrated in section on line b—b in Figure 6.

The other two rollers are in mesh by their gear pinions 40 with the gear 46 also in the shape of a ring and resting on the tooth, ring or gear 45. The gears 45 and 46 are supported by a suitable annular plate 47. The ring or gear 45 is provided with the stud 48 around which the jaw 49 of the lever 50 fits, the lever 50 being pivoted at 51 on the bracket 52 which is in fixed position and fastened to the foot 53 on the non-rotating stem 15.

The lever 50 is provided with a roller 54 which fits in the cam slot 55 in the head 20. A similar lever 56 is pivoted at 57 and has its jaw 58 engage a stud 59 in the upper gear 46. The slot 55 is shaped so that as the head, which is provided with this slot is rotated, actuates the levers 50 and 55 in proper sequence to cause the crimping tools 27 to be moved by their eccentrics in a more rapid manner when on the short side of the can so that the corner of the can is rounded with the entire crimping or seaming action since the gear 45 is rapidly and sharply moved in the reversed direction.

Those tools, however, that are traversing

the longer side of the oblong can are delayed until they arrive at the corner since the parts are moved by the slot 55 to cause the gear 45 to move with the head for a short distance so that it moves around at nearly the same speed as the head and then when this acceleration is retarded by the slot the normal operation of the eccentric 39 takes place and the tool is then moved around to crimp the corner of the can.

In this application it has been necessary to describe a square can and an oblong can so that the operation of the parts will be clearly understood. These designations, however, have simply been for convenience and it is understood that so far as this specification and the claims are concerned, polygonal defines any can other than cylindrical since many shapes of cans are now made and by oblong is also included oval cans or any other can that has irregular sides.

It will be evident that the details of this construction can be changed without departing from the scope of the invention.

I claim:

1. A machine for crimping the edges of cans of polygonal shape comprising a can holder, a support, a rotatable head in the support, an eccentric in the head, a pinion on the eccentric, a gear fixed against rotation and with which the pinion is in mesh, and a crimping tool supported from the eccentric so that when the head rotates, the crimping tool follows a polygonal path.

2. A machine for crimping polygonal cans comprising a support, a head rotatably arranged on the support, a crimping tool, an eccentric on the head, a pinion on the eccentric and a gear with which the pinion is in mesh whereby when the head is rotated the eccentric is actuated to project and then retreat the crimping tool at intervals so that it follows a polygonal path.

3. A machine for crimping polygonal cans comprising a support, a head rotatably arranged on the support, a crimping tool, an eccentric on the head, a pinion on the eccentric, a gear on the support and in mesh with the pinion, and means for swinging the gear at intervals so that the tool is caused to follow an oblong path.

In testimony that I claim the foregoing, I have hereto set my hand, this 26th day of March, 1924.

JAMES H. GORDON.
